UNITED STATES PATENT OFFICE

MARK H. STRATTON, OF RIDGEWOOD, NEW JERSEY, ASSIGNOR TO GRIPLOCK INCORPORATED, OF NEW YORK, N. Y., A CORPORATION OF DELAWARE

WIRE-STRAPPING TOOL

Application filed November 22, 1927. Serial No. 234,997.

This invention relates to a wire strapping tool designed for tensioning and fastening wire straps or the like around packages.

It has for an object to provide such a device that embodies various improvements in the form, construction and arrangement of the several parts, whereby its designed function is more rapidly and efficiently performed than with previous devices of this nature, and whereby strength, rigidity, and durability are attained to a high degree.

Another object consists in providing a device of this character which is more readily manufactured, assembled, disassembled and adjusted than previous devices.

A practical embodiment of the invention is represented in the accompanying drawings in which

Fig. 1 represents a top plan view of the tool,

Fig. 2 represents a side elevation thereof,

Fig. 3 represents a side elevation reverse to Fig. 2,

Fig. 4 represents a horizontal section taken in the plane of the line IV—IV of Fig. 3 looking in the direction of the arrows,

Fig. 5 represents a detail vertical section taken in the plane of the line V—V of Fig. 3 looking in the direction of the arrows,

Fig. 6 represents a detail side elevation showing the parts in one position of the operation,

Fig. 7 represents a similar view showing the parts in another position.

Fig. 8 represents a horizontal section taken in the plane of the line VIII—VIII of Fig. 7 looking in the direction of the arrows,

Fig. 9 represents a detail vertical section taken in the plane of the line IX—IX of Fig. 3 looking in the direction of the arrows,

Fig. 10 represents a detail side view of the crushing and cutting elements, parts being removed to show those lying beneath,

Fig. 11 represents a detail vertical section of the means for adjusting the gripper arm, and

Fig. 12 represents a horizontal section taken in the plane of the line XII—XII of Fig. 11 looking in the direction of the arrows.

50 The subject matter of this invention is of

the same general nature as that disclosed in United States patent to W. N. Lurcott, No. 1,616,912 dated February 8, 1927, and it is calculated to tension, fasten and sever wire straps of the general kind described in the 55 said patent, which straps have a coil at one end and are fastened or secured by passing the other end through the coil and then crushing the latter, at which last named operation the free end of the strap is also severed.

60 The tool has a main body or frame which includes a base denoted generally by 1 and an uprising portion denoted generally by 2. The various parts are operatively supported or carried by the said frame.

65 One group of mechanism is designed to grip the wire strap at a point adjacent the coil end in order to hold it during tensioning, crushing and severing. This group includes a pair of gripping jaws, one of which consists of a 70 plate 3 that is secured to the base by screws 4, as shown in Figs. 2 and 4. This plate 3 has serrations formed on both its sides, whereby it may be reversed in case of wear.

75 The other jaw is marked 5 and it depends from the protruding end of an arm 6 that is mounted to slide in a web 7 cast integrally with the frame of the device. The face of this jaw 5, designed to cooperate with plate 3, is also provided with serrations.

80 The inner end of the arm 6 is pivoted at 8 to another arm 9 that is pivoted at 10 on the base 1. The said connection between the arms 6 and 9 is made adjustable by means of an hexagonal nut 11 (Figs. 11 and 12) which 85 fits within a corresponding opening in the arm 6 and is eccentrically mounted on the pivot 8, which latter consists of a screw that is threaded into the eccentric nut 11 and its own nut 12. This adjustability provides for 90 compensating wear on the teeth of the jaws so as to insure a firm grip upon the wire in all cases.

95 A coil spring 13 surrounds the pivot 10 and has one end secured to the arm 9 and the other to a pin 14 fixed in the base 1. The tension of this spring is such as normally to urge the arm 6 in an outward direction so that its jaw 5 is not in operative relation with the jaw 3. It will be observed, by reference 100

to Fig. 3, that the pivot screw 10 is threaded into a bearing pin 10* that has a driving fit in the base 1. This bearing pin receives the convolutions of the spring 13, which has three full turns around it, and the construction provides a very strong spring action and also tends to obviate breakage of the pivot screw 10.

Means is provided for moving the arm 6 so as to bring the said jaws into cooperative relation for gripping the wire strap adjacent the coil, as previously mentioned; and this means comprises a lever 15 (see Figs. 6 and 7) that is pivotally mounted in bearings 16, 17 (Fig. 1) cast integral with the machine frame. The said lever has a nose 18 which is calculated to engage the end 19 (Fig. 8) of a rod 20 that is mounted to slide in webs 21, 22, formed on the machine frame. The end 19 of the said rod has a laterally projecting lug 23 that has a curved face and slanted end designed to engage with the arm 9. As the lever 15 is swung to the right (Figs. 6 and 7), its nose 18 engages the end 19 of rod 20 and moves the same to the left, which movement causes the curved face of the lug 23 to engage the curved end of the arm 9 and move the latter rearwardly against the tension of spring 13. This movement continues until the slanting end of lug 23 enters a notch formed in arm 9 and abuts a corresponding face constituting one side of the said notch, as clearly shown in Fig. 8. In Fig. 6 the parts are shown before the lever 15 is swung to cause this operation, and in Figs. 7 and 8 the parts are shown after the movement has been completed. This results in a swinging of the arm 9 around its pivot and retraction of the arm 6 until the jaws 3 and 5 are in cooperative relation for gripping the strap, which relation is indicated in Fig. 8. The end of the lug 23 engaging the corresponding face on the arm 9 will hold the parts in this position, until the rod 20 is moved in the opposite direction, as will be hereinafter described. When the rod 20 is brought to the limit of this movement, its inoperative end abuts a stop 24 consisting of a web on the frame, thereby relieving a certain amount of wear and strain on the lug 23 and arm 9.

The slot in the web 7 in which the arm 6 slides is somewhat wider than the said arm and, during the sliding movement, the latter is yieldingly held at one side of said slot, as shown in Fig. 4, by a plunger 25 that is housed in the frame of the machine and backed by a spring 26 and adjusting nut 27. This allows a slight lateral movement of the arm 6 while maintaining it substantially in the desired position for effective operation.

With the parts in this position the wire strap A is firmly gripped at a point adjacent its coil end, as indicated in Fig. 2, and the next step of tensioning the strap may proceed. In order to accomplish this step the free end of

the wire must be passed around the package and inserted through the coiled end.

Before the free end of the strap is passed through the coil, it is led between guides 28, 29 (Fig. 1) that are pivoted on a screw 30 set into the frame. The arrangement of these guides is such as to provide a slight opening therebetween for reception of the strap. The free extremity of the latter, after traversing the coil, is led underneath a boss 31 that is cast integral with a face plate 32 which is secured to the frame by bolts 33 and nuts 34. The said end is pulled into a hook 35 carried on the arm 6 above the jaw 5 and bent upwardly into engagement with projecting teeth 36 of a hub 37 that is rotatably mounted in the bearings 16 and 17.

It should be said that, in practice, the strap will ordinarily be passed loosely around a package and its free end inserted through the coil before any part is brought into engagement with the tool. The strap may then be moved sideways so as to cause the proper parts of the wire to lie between the jaws 3 and 5 and between the guides 28 and 29, at which juncture the free end is bent upwardly through the hook 35 so as to be in line with the teeth 36. If the lever 15 is then swung so as to slide the arm 6 into gripping position, as previously described, the movement of the hook 35 carried by the said arm will automatically press the free end of the strap against the teeth 36, whereupon the same will enter between the said teeth upon rotation of the hub 37, as will hereinafter be described.

In order to insure that the strap will be in the proper vertical position with respect to the jaws 3 and 5, a lug 38 is cast on the frame of the machine in such position as to overlie the strap and prevent it from rising above the jaws.

The tensioning of the strap is effected by the lever 15 after the jaws 3 and 5 are in gripping position, and this is accomplished by a pawl 39 which is pivoted on a bolt 40 that traverses the lever 15, which pawl is adapted for engagement with a ratchet 41 that is fixed by a key 42 (Fig. 5) to the hub 37, and which has its own hub entering the lever 15 so as to constitute an immediate bearing for the latter and permit relative rotary motion of the lever and ratchet. The pawl is held in contact with the ratchet by an expansion spring 43 that enters a recess in the pawl and has one end fast to a pin 44 projecting from the lever 15.

The fact that the hub and ratchet are formed separately enables them to be hardened to different degrees. It is desirable to make the hub quite hard in order to withstand wear, but a similar hardening of the ratchet would promote a tendency of its teeth to chip.

In order to prevent backward movement of the ratchet after it has been urged in one

direction by the lever 15 and pawl 39, a retaining pawl 45 (Fig. 2) is mounted on a screw 46 set in the frame and urged into engagement with the ratchet by a spring 47 that enters a recess in the pawl and has one end fast to a pin 48 also fixed in the frame.

When the free end of the strap has entered between the teeth 36, oscillation of the lever 15 will rotate the ratchet 41 and hence the hub 37 so as to draw the said end of the strap through the hook 35 and through the coiled end until the proper tensioning has been attained, the bend of the strap about the hook and its insertion between the teeth 36 preventing slippage during its operation, which effect is also assisted by the roughening or milling of the outer sides of the teeth, as shown in Fig. 1. The movement of the free end of the strap while being tensioned is facilitated by a guide roller 49 (Fig. 1) that is mounted in the frame at the rear of the boss 31. After sufficient tension has been attained, the lever 15 is allowed to rest in horizontal position shown in Fig. 2.

The strap is now in position for fastening and severing of the free end and this is accomplished by the mechanism which will now be described.

A pair of crushing levers 50, 51, have their inner ends downwardly curved and keyed to a pair of shafts 52, 53 (see Fig. 2). These shafts are identical, and one of them, 53, together with its mounting, is shown in Fig. 9. The lever 51 is here shown as fixed to the shaft by a key. The shaft 53 is journaled with a long and short bearing in an integral portion of the frame, the long bearing being adjacent the end to which lever 51 is secured in order to withstand the force exerted on the lever. The shaft has an intermediate eccentric portion 54 that is let into the concave upper end of one of two identical thrust bars 56, 57. (Fig. 10.) The eccentric portion of the other shaft is marked 55 and is let into thrust bar 57.

The lower ends of the said thrust bars are curved and set into corresponding grooves formed in a crushing block 58, which latter is held in engagement with the thrust bars by a retractile spring 59 that has one end fast to the crushing block and the other end fast to a pin 60 set in the frame. A spacing spring 61 is hung on the pin 60 and its free ends engage the thrust bars 56, 57, in order to normally urge them apart and hold them steadily in their position.

The crushing block 58 has a cutter 62 fixed therein adapted to cooperate with a hole 63 formed in the anvil and base of the device, and it will be noted that the base is relatively thick at this point in order to withstand the pressure of the cutting operation. Added rigidity at this point is also provided by a fillet 63* which connects the part of the base

that supports the anvil with the main portion of the base.

The anvil proper (Fig. 9) consists of a plate 64 of hardened material which has a dovetailed portion 65 set into a correspondingly shaped groove in the base of the device. The plate 64 is fastened in position by a rivet, or the like, 66.

The levers 50 and 51 are secured on the shafts 52, 53, by nuts 67, 68, (Fig. 3) and the hubs of the said levers are fashioned in the shape of gears 69, 70, which mesh with each other so that the levers move in unison and form, in effect, compound mechanism for actuating the crushing block 58.

In order to determine the movement of the said levers 50, 51, they are provided with lugs 71, 72, in which are threaded adjustable screws 73, 74, which may be fixed in desired position by lock nuts 75, 76. The limit of the operative swing of the said levers is determined when the heads of the said screws abut, which position is approximated in Fig. 6. It is desirable to change this adjustment to take up wear on the parts.

To operate the crushing or fastening and securing means, the crushing levers 50 and 51 are seized and swung in opposite directions from the position shown in Fig. 3 until the heads of the screws 73, 74 abut. This movement of the levers rotates the shafts 52, 53 and causes their eccentric portions, marked 54, 55, to actuate the thrust bars 56, 57, so as to depress the crushing block 58, and cutter 62 carried thereby. It will be understood that the coiled end of the strap with the free end traversing the same lies in the path of movement of the crushing block, and that the free end of the strap where it leaves the coil is held by the guides 28, 29, roller 49 and hook 35 in the line of movement of the cutter 62. The guides are so efficient that the coil on the strap can be placed in the tool either side up and yet the correct portion of the strap will be severed by the cutter. This is also facilitated by the tapering shape of the cutter, (see Figs. 9 and 10). The correct position of the coil longitudinally of the parts is insured by a pair of leads 32* which consist of lugs projecting downwardly from the face plate 32. By reference to Figs. 2 and 9, it will be seen that these are tapered in both vertical and longitudinal planes, thereby providing a funnel-like guide for leading the coil to the desired correct position.

Downward movement of the crushing block serves to flatten the coil and corrugate the free end of the strap lying therein, as set forth in the Lurcott patent above named, and also described in Lurcott patent No. 1,474,372 dated November 20, 1923, thereby fastening the strap in its tensioned condition about the package. This movement of the crushing block will also cause the cutter 62 to sever the free end of the strap at a point adjacent

the coil, and the parts are so adjusted that this severing takes place just before the crushing action is entirely completed but after it has been sufficiently completed to lock the ends of the strap against slippage.

This movement of the crushing levers 50, 51, also brings about release of the jaws 3 and 5 so as to free them from engagement with the strap. This result is effected by a dog 77 (Figs. 1, 3, 6 and 7) which is formed on the hub of lever 50 and is arranged to contact with an adjustable stop 78 carried on the slide rod 20. When the dog 77 meets stop 78 it pushes the latter and hence slides the rod 20 so as to move the lug 23 out of engagement with the arm 9, and thus permit spring 13 to swing arm 9 and arm 6 into the inoperative position shown in Fig. 4. The stop 78 is adjusted in such position on shaft 20 that this release takes place just as the crushing operation is completed, and it is an important consideration that these operations shall be properly timed if the device is to operate satisfactorily, because too early release of the jaws 3 and 5 would permit insufficient crushing of the strap if the operator were careless, while an adjustment of the stop 78 too far in the other direction would prevent any release of the said jaws by the movement of the crushing lever 50. It is highly desirable to obtain a uniform crushing and consequent fastening of the strap in every case and, with this thought in mind, the stop 78 is so constructed that it can be set by one in charge and not be readily reset by another operative. As shown in Fig. 4, the stop is formed of two parts held together by a screw 79 and nut 80. The said nut 80 is adapted to be engaged by a wrench of particular form, not available to an ordinary operative, and it is surrounded by a loose ring 81 which may be engaged by an ordinary spanner, or the like. Accordingly, any effort of an operative to change this adjustment would consist in his applying an ordinary spanner or the like to the ring 81, and turning the same, but this turning movement will be entirely ineffective because there is no fixed connection between the said ring and the nut 80 which locks the stop 78 on the rod 20.

As the lug 23 moves out of engagement with the arm 9, due to the actuation of the slide rod 20 by the crushing lever 50, the spring tension of the arm 9 will throw the said lug and rod rapidly to the right (Figs. 6, 7 and 8), and I provide a stop 82 secured to the frame by bolt 83, with which stop the end 19 of the rod 20 may contact for determining its movement. The provision of this stop relieves the strain on the parts and, if desired, the stop may be made adjustable as, for instance, by a slotted engagement with the bolt 83.

65 It will be observed, by reference to Figs.

1 and 3, that the crushing levers 50 and 51, when in their position of rest, lie with their extremities considerably above the base of the device. This is an advantage because it prevents the said extremities from becoming entangled with the strap, and this limit of movement is fixed by a projection 84 on the hub of lever 51, with which projection the under side of lever 50 contacts, as indicated in Fig. 3.

70 The ends of the levers 15, 50 and 51 may be provided with suitable handles, as indicated in the drawings.

75 Inasmuch as the operation of the device has been described in connection with the description of the different groups of mechanism for accomplishing the several functions, it is not deemed necessary to repeat the same.

80 It will be understood that various changes may be resorted to in the form, construction and arrangement of the several parts without departing from the spirit and scope of my invention; and hence, I do not intend to be limited to the details herein shown and described, except as they may be included in the claims.

85 What I claim is:

1. A device of the character described comprising, wire gripping mechanism normally urged in one direction, means for moving the said mechanism in the opposite direction, and an adjustable connection for determining the point in its movement at which the gripping becomes effective.

90 2. A device of the character described comprising, wire gripping mechanism normally urged in one direction, means for moving the said mechanism in the opposite direction, and an adjustable connection for determining the point in its movement at which the gripping becomes effective, said connection including an angular nut eccentrically mounted.

95 3. A device of the character described comprising, wire gripping mechanism normally urged in one direction, means for moving the said mechanism in the opposite direction, and an adjustable connection for determining the point in its movement at which the gripping becomes effective, said connection including a pivot and an angular nut eccentrically mounted on said pivot.

100 4. A device of the character described comprising, a crushing block, shafts designed to operate said block, and thrust bars directly engaging said shafts and said block.

105 5. A device of the character described comprising, a base, means for crushing and severing a strap, said means being adapted to cooperate with said base, and said base having a thickened portion in register with the severing means.

110 6. A device of the character described comprising, a base, means for crushing and

severing a strap, and an anvil for cooperating with said means, said base having a thickened portion in register with the severing means and said anvil consisting of a plate of hardened material having an undercut connection with the base.

7. A device of the character described comprising, means for crushing and severing a strap, a support for the strap during these operations, and a double guide located adjacent each end of the support for holding that portion of the strap to be severed in register with the severing means.

8. A device of the character described comprising, a frame, means for tensioning a strap, said means including a rotary element having teeth integral therewith, said teeth being provided with roughened surfaces.

9. A device of the character described comprising, means for gripping a strap, means for crushing a strap and means for severing a strap, mechanism for releasing the gripping means, and a device for predetermining the moment of release in order properly to synchronize said operations, said device being adjustable and being arranged to conceal its means of adjustment.

10. A device of the character described comprising, means for gripping a strap, means for crushing a strap and means for severing a strap, mechanism for releasing the gripping means, and a device for predetermining the moment of release in order properly to synchronize said operations, said device having an element for adjusting it and an apparent element for adjusting it which has no adjusting effect.

11. A device of the character described comprising, means for gripping a strap, means for crushing a strap and means for severing a strap, mechanism for releasing the gripping means, and a device for predetermining the moment of release in order properly to synchronize said operations, said device having an element for adjusting it, said element having an adjusting nut and a movable ring surrounding the nut the movement of which ring has no effect.

12. A device of the character described comprising, means for gripping a strap, means for crushing a strap, means for severing a strap, and mechanism for releasing the gripping means, said mechanism including a reciprocating rod provided with a fixed stop at one end and an adjustable stop at the other.

13. A device of the character described comprising, means for crushing and severing a strap, devices designed to operate said means, and adjustable stops carried by said devices and arranged to determine the limit of movement thereof by contact with each other.

14. A device of the character described comprising, wire gripping mechanism, means

for normally urging said mechanism in one direction, said means including a pivot, an element movable around said pivot, a bearing in which said pivot is mounted, and a coil spring surrounding said bearing and engaging said element.

15. A device of the character described comprising, wire gripping mechanism, means for normally urging said mechanism in one direction, said means including a pivot, an arm movable around said pivot, a bearing pin in which the pivot is mounted, said bearing pin being carried in the base of the device, and a coil spring surrounding said bearing pin and having one end engaging the arm and the other end engaging the base.

16. A device of the character described comprising, means for crushing a strap, and means for guiding the portion of the strap to be crushed so as to insure its correct positioning longitudinally of the crushing means.

17. A device of the character described comprising, means for crushing a strap, and means for guiding the portion of the strap to be crushed so as to insure its correct positioning longitudinally of the crushing means, said guiding means including tapered elements.

18. A device of the character described comprising, means for crushing a strap, and means for guiding the portion of the strap to be crushed so as to insure its correct positioning longitudinally of the crushing means, said guiding means including elements each tapered in a plurality of planes.

In testimony that I claim the foregoing as my invention, I have signed my name this 21st day of November, 1927.

CERTIFICATE OF CORRECTION.

Patent No. 1,776,868.

Granted September 30, 1930, to

MARK H. STRATTON.

It is hereby certified that error appears in the printed specification of the above numbered patent requiring correction as follows: Page 5, line 59, claim 13, before the word "devices" insert the words a pair of cooperating; and that the said Letters Patent should be read with this correction therein that the same may conform to the record of the case in the Patent Office.

Signed and sealed this 21st day of October, A. D. 1930.

**M. J. Moore,
Acting Commissioner of Patents.**
